UNITED STATES PATENT OFFICE.

FREDERICK SCHIMPER, OF UNION, NEW JERSEY, ASSIGNOR OF ONE-HALF TO
ALFRED H. KOELLER, OF RIDGEFIELD PARK, NEW JERSEY.

WIND-SHIELD.

1,026,408.

Specification of Letters Patent.

Patented May 14, 1912.

Application filed January 24, 1912. Serial No. 673,020.

To all whom it may concern:

Be it known that I, FREDERICK SCHIMPER, a citizen of the United States, residing in the town of Union, county of Hudson, and 5 State of New Jersey, have invented a new and Improved Wind-Shield, of which the following is a specification.

This invention relates to a wind shield for automobiles which can be so adjusted in 10 case of storm that the rain beating against the shield will not obstruct the free view of the driver or passengers.

In the accompanying drawing: Figure 1 is a perspective view of a wind shield embodying my invention. Fig. 2 an end view showing the upper shield sections unfolded; Fig. 3 a similar view with the upper sections folded; Fig. 4 a front view of the top shield-member; Fig. 5 a detail of the spring 20 hinge, and Fig. 6 an enlarged cross section on line 6—6, Fig. 1.

The wind shield comprises essentially a lower fixed member 10 fitted into an upright frame 11, and constituting the main 25 body of the device. The side rails 11^a of frame 11 extend a distance beyond the top rail 11^b thereof, and are by braces 12 rigidly secured to the body of the car. To the upper ends of side rails 11^a is pivoted by 30 spring hinges 13 the frame 14 of a foldable top member 15. To the inner or lower side of top member 15, there is in turn hinged the frame 16 of an intermediate member 17 by means of lugs 18 that extend inwardly 35 from frame 14 and carry the pivot pins 19. Lugs 18 should be set at a substantial distance back of the lower or outer end of member 15, so that such member is adapted to project a corresponding distance beyond 40 the upper end of the intermediate member 17 and to thus constitute an overhanging roof. The body of the intermediate member 17 is made of glass or other transparent material to form a window and the lower rail 45 16^a of its frame is adapted to be removably supported upon the top rail 11^b of lower member 10. To this effect rail 16^a is provided with a longitudinal groove 16^b which snugly encompasses the corresponding edge 50 of rail 11^b (Fig. 6). A catch 20 on rail 16^a adapted to engage rail 11^b serves to securely hold member 17 in its unfolded position.

In case of good weather, top member 15 is lowered against the outer side of bottom member 10, while intermediate member 17 is folded against the inner side of such bottom member. This latter operation may be accomplished owing to the fact that the frame 16 of member 17 is made so much narrower 60 than frame 11 of bottom member 10 that it may be passed freely through the same, while at the same time, the lugs 18 will be projected through frame 11, and thus carry member 17 beyond the inner face thereof. 65 After the members have been folded in the manner described, they are locked in position by a pair of catches 21 on side rails 11^a that engage over the corresponding rails of frame 16 (Fig. 3). 70

In case of bad weather, the device is unfolded by pushing member 17 outward and upward until its bottom rail 16^a becomes seated upon rail 11^b to which it is locked by catch 20. In this position member 17 will 75 project outwardly and upwardly from the top of member 10, while member 15 will extend outwardly and downwardly over member 17 and overhang the same to a considerable extent (Figs. 1 and 2) so that member 17 is effectively protected from the rain, and a clear vision is insured. In order to prevent the rain from dropping from member 15 upon member 17, the bottom rail 14^a of the former is provided with a gutter 22 80 that slopes gradually from the center toward the ends of the rail and thus discharges the water to the right and left of the window.

It is obvious that the pivotal connection of the intermediate member 17 may be 85 formed between such member and the top rail 11^b of lower member 10, in which case the upper end of member 17 would abut against the lower side of top member 15 at a distance back of the free end thereof. 90

I claim:

1. A wind shield comprising a lower fixed member, a frame extending upwardly beyond the same, an upper member pivoted to said frame, an intermediate member pivoted to the upper member at a distance from the free end thereof, and means for removably connecting the lower end of the intermediate member to the upper end of the lower member. 100

2. A wind shield comprising a lower fixed 105

member, a frame extending upwardly therefrom, an upper member pivoted to the frame, an intermediate member pivoted to the upper member at a distance back of the 5 free end thereof, said intermediate member being adapted to be passed through the frame of the lower member, and catches adapted to secure the intermediate member to said frame.

FREDERICK SCHIMPER.
